UNITED STATES PATENT OFFICE.

JOHN W. IRVIN, OF CHADRON, NEBRASKA, ASSIGNOR OF THREE-TENTHS TO ELIHU BOND, JOSHUA D. WOODS, WILLIAM A. HARPER, LUTHER W. BOWMAN, ADAM D. WAGONER, AND LINDLEY W. GORTON, OF HAY SPRINGS, NEBRASKA.

CAR-COUPLING.

SPECIFICATION forming part of Letters Patent No. 579,981, dated April 6, 1897.

Application filed November 16, 1895. Renewed September 30, 1896. Serial No. 607,499. (No model.)

To all whom it may concern:

Be it known that I, JOHN W. IRVIN, a citizen of the United States, residing at Chadron, in the county of Dawes and State of Nebraska, have invented certain new and useful Improvements in Car-Couplings; and I do hereby declare the following to be a full, clear, and exact description of the invention, such as will enable others skilled in the art to which it applies to make and use the same.

This invention relates to certain new and useful improvements in car-couplings, having for its objects, among others, to provide a simple and improved cheap coupling composed of few parts and those so arranged as to be positive in their action and not liable to derangement or injury.

Other objects and advantages of the invention will hereinafter appear, and the novel features thereof will be particularly pointed out in the appended claim.

The invention is clearly illustrated in the accompanying drawings, which, with the letters of reference marked thereon, form a part of this specification, and in which—

Figure 1 is a perspective view showing my improvement. Fig. 2 is a vertical longitudinal section through the draw-head.

Like letters of reference indicate like parts throughout both views.

Referring now to the details of the drawings by letter, A designates the draw-head, of usual construction, provided with the mouth a, which is extended rearwardly in a substantially rectangular horizontally-disposed recess a'. To the rear of this recess is a horizontal pin or bolt B, upon which is pivoted the latching-hook C, adapted to work in a vertical slot in the upper wall of the draw-head, its front portion being cam-shaped and terminating in a hook to the rear of said face with a slightly-rounded recess b', in which the link is adapted to rest after the same is engaged with the hook. The rear end of the latching-hook rests upon a spring D, seated in a chamber d in the draw-head, and which spring serves to normally keep the front end of the hook down. The hook is provided upon its upper face near its front end with a

ring or eye E, in which is engaged a link F, 50 pivotally connected with the longitudinal arm g of the shaft G, which latter runs parallel with the front end of the car and is mounted in suitable bearings g' thereon, its outer end terminating in a crank-handle G², by means 55 of which the coupling-hook may be raised to uncouple the cars when desired. This shaft has slight endwise play in its bearings to permit of its engagement or disengagement with a lateral pin H on the side of the car, with 60 which the crank-handle is engaged when it is desired to hold the coupling-hook permanently against coupling.

The operation will be readily understood from the foregoing description when taken in 65 connection with the annexed drawings, and a further detailed description thereof will not be necessary.

The improvement may be applied to a box-car or a flat car.

Importance is attached to the bevel in the draw-head, whereby the coupling is more easily accomplished.

X is a dog on the side of the car to prevent the cars from coupling when so desired.

What I claim as new is—

The improved car - coupling herein described, comprising in combination, the draw-head having its mouth provided with rearwardly-extending rectangular horizontally-disposed recess, a horizontal pin to the rear of this recess, the lower face of the recess being provided with a concavity, a latching-hook pivoted on said pin and having a depending curved portion fitting said concavity, 85 with a cam-faced front end with a curved hook to the rear of the same and upon its upper face in front of its pivot provided with an eye, a spring seated in a vertical socket in the draw-head to the rear of said horizontal pin and bearing against a downward extension on the rear end of the arch, a link pivotally connected with the said eye, a shaft extended parallel with the front end of the car and mounted in suitable bearings thereon 90 provided with a longitudinal arm integral therewith and pivotally connected with the upper end of said link, the said shaft having

slight endwise play in its bearings and its outer end terminating in a crank-handle, and a lateral pin on the side of the car, with which said crank-handle is adapted to be engaged and from which it is disengaged by endwise movement of the shaft, all substantially as herein shown and described.

In testimony whereof I have signed this specification in the presence of two subscribing witnesses.

JOHN W. IRVIN.
